EDMUND O. SCHWEITZER AND NICHOLAS J. CONRAD, OF CHICAGO, ILLINOIS,
ASSIGNORS TO SCHWEITZER AND CONRAD, OF CHICAGO, ILLINOIS, A CORPO-
RATION OF ILLINOIS.

LIGHTNING-ARRESTER.

1,164,757.

Specification of Letters Patent. Patented Dec. 21, 1915.

Application filed March 20, 1915. Serial No. 15,783.

To all whom it may concern:

Be it known that we, EDMUND O. SCHWEITZER and NICHOLAS J. CONRAD, citizens of the United States, residing at Chicago, in the county of Cook and State of Illinois, have invented a certain new and useful Improvement in Lightning-Arresters, of which the following is a full, clear, concise, and exact description, reference being had to the accompanying drawings, forming a part of this specification.

This invention provides an improved lightning arrester.

The present invention is a further advance along the line of development pointed out in our co-pending application Serial No. 866,214, filed October 12th, 1914. In that application we have disclosed a horn gap lightning arrester in which the movement of the dynamic arc along the horns of the arrester automatically includes resistance in series with the arc but externally thereof, while preserving at all times the original gap for relieving a second discharge.

The plain horn gap lightning arrester as known and constructed according to the prior art is inherently defective, but it has such great practical advantages, being simple, inexpensive, of rugged construction and requiring no attention after once being installed, that it persists in the field in spite of its disadvantages.

The horn gap lightning arrester, by flashing over, relieves at once the excessive potential on the line, but the relief is heroic; instead of discharging only the potential in excess of the normal line potential, the horn gap arrester practically short circuits the line and discharges the entire potential on the line. This action is effective in relieving excessive potential, but it is needlessly severe. However, the action is due to the characteristics of this type of apparatus. The initial discharge occurs across the point of least resistance and the arc which is then established is itself the only resistance in the circuit. It can be seen at once that this is like a fusible plug in a boiler, which, when it "lets go," always allows a greater discharge of pressure than is necessary.

We have conceived the idea of building a horn gap arrester so that the tendency will be to discharge only the excessive pressure and not the line pressure. Specifically we

do this by providing a series of discharge paths of different discharge capacities, the ones of lowest discharge capacity coming into operation as soon as the pressure shows a given predetermined excess over line pressure. The paths of greater discharge capacity come successively into operation in case the first path is insufficient to relieve the pressure. This is analogous to a series of pop valves of successively increasing discharge capacity, set at successively increasing discharge pressure. For instance, if a one inch pop valve set at 100 pounds per square inch cannot relieve the accumulated excess pressure, a one and one-half inch valve set at 102 pounds per square inch will then come into play and, if these are still insufficient, then a two inch valve set at 105 pounds pressure may come into play, and so on, successively, until the excess pressure, no matter how great, is entirely relieved. Such an arrangement will retain always the pressure at which the first one is set to discharge. One manner in which we can construct the apparatus for embodying this idea is to provide a series of spark gaps made into a horn gap form, or otherwise, and allow the potential to discharge through resistances, the setting of the gap determining the excess of pressure required to cause the discharge, and the resistance in the circuit of the gap determining the discharge capacity thereof. The short gap, having high resistance in series, is set to break down first, and the next gap will tend to break down thereafter, and so on, successively; but we counteract the tendency to break down and discharge which occurs in the gap adjacent the one which is discharging, by a powerful blowout arrangement, the activity of which is augmented by an increased discharge. This blowout arrangement, while it is particularly adapted for use in this form of arrester, is also very valuable in other forms, and we have therefore illustrated a number of modifications in which it is used and are describing it as it is employed in a variety of forms of arrester. We have also found the blowout arrangement to be applicable to the horn gap arrester as previously constructed.

The open horn gap arrester is unreliable. This unreliability is due to a variety of causes, some of which are known and can be com-

bated, and some of which are unknown and can, at best, be only guessed at. Sometimes the spark gap will fail to break down and relieve the static on the line by discharging as it should. It also fails at times to break the arc promptly, so that the arc, instead of rising quickly and breaking as it should, often hangs on and holds a destructive short circuit on the generators or other apparatus. These failures in operation can generally be ascribed to wind or other atmospheric conditions and to the fact that the discharge to be dealt with varies within limits of enormous range. If the gap is set for a low value discharge, the dynamic current is likely to hang on and cause damage, either by its continued existence or by the sudden breaking of a large current. If the gap is set for high values then the lesser disturbances on the line, which are not relieved, are likely to cause damage. We have found a simple solution for this difficulty. We construct the arrester to embody the above-mentioned blowout arrangement, so that the arc is compelled to move out and break itself regardless of the quantity or rate of discharge or the point of formation. At the same time that the arc moves the current forming the arc is caused to decrease. This we accomplish by sectionalizing one or both of the electrodes and inserting resistances between the sections, or by depending solely upon the lengthening of the arc itself between the electrodes. Being thus enabled to prevent formation of an excessive discharge and to break any discharge that does form, we can set the arrester at a relatively low value and thus cope with any situation. We secure the positive break or blowout by confining the space within which the arc forms to a degree sufficient to cause either a bomb or explosive effect or a chimney effect, or a combination of the two. To this end we construct the electrodes in such manner that they form a confined space between them at the points where the arc forms. This is accomplished specifically by forming one electrode in the shape of a central core and the other in the shape of an outer generally cylindrical shell surrounding the core in whole or in part. Incidentally we secure a number of marked advantages, all of which form part of the present invention. The above arrangement prevents disturbance from wind and gives a greater uniformity of discharge and among other advantages it provides greater electrostatic capacity and hence offers greater ease of discharge for currents of high frequency. It offers also a simple and workman-like mechanical solution of the problem of construction.

In order to set forth with more particularity the nature of our invention, so that the same may be readily understood, con-

structed and employed by those skilled in the art, reference is here made to the appended drawings which form a part of this specification.

Figure 1 is a vertical sectional elevation of one form of arrester. Fig. 2 is an elevation of the central electrode or core with the outer casing and the bands thereon broken away to expose the interior connections. Fig. 3 is a vertical sectional elevation of a slightly different form of construction with the connections shown diagrammatically. Fig. 4 is a fragmentary elevational view of a cone of insulation with the electrode formed of converging strips of metal. Fig. 5 is a plan view of one of the resistance units 13 shown in Fig. 2. Fig. 6 is a vertical sectional view of another form in which our invention may appear. Fig. 7 is a detail view illustrating the manner in which the core is built up. Fig. 8 is a vertical sectional elevation of a form in which the core is built up of annular segments of alternate resistance material and conducting material. Fig. 9 is a similar view of a form in which the shell and core are both sectionalized and in which an adjustable annular air gap is provided. Fig. 10 is a vertical sectional elevation of another form of arrester having adjustable spheres for determining the paths or air gaps for a current of different frequency. Fig. 11 is a vertical sectional elevation of an inverted form of arrester. Fig. 12 is a plan view of the inner electrode as viewed on the line 12-12 of Fig. 11. Fig. 13 is a diagram showing a number of arresters connected in series; and Fig. 14 is a similar diagram showing a number of arresters in series, the arresters having a common equalizing connection to maintain a common potential across all the air gaps.

The arrester shown in Fig. 1 comprises an outer shell electrode 1 and an inner core electrode 2, these electrodes being separated by an open annular space which forms an air gap between them. The shell 1 comprises a lower cylindrical part 3 and an upper flaring part, secured thereto or formed integral therewith, the shell being supported on insulators 5-5 by means of brackets 6-7 and braces 8 between the brackets and the shell. The shell is supported on insulators at three or more points in order to steady the same.

The core electrode 2 is formed of an upper conical part, which may be formed of sheet metal, as shown in Figs. 1 and 2, and a lower conical part 4, which comprises a number of metallic bands 11, mounted upon a body of insulation. Suitable resistances are connected between the bands so that when an arc is formed between the shell 1 and the upper band 11, which is nearest to the shell, sufficient resistance will be in-

cluded in the circuit to prevent an excessive discharge and consequent drop in voltage and to damp out line surges and high frequency oscillations.

5 Fig. 2 illustrates one manner in which the core 2 may be built up. In this form the upper cone 9 is made of sheet metal secured to a lower cone or frustum 12, of insulating material. The lower cone 12 is hollow and 10 contains within it a number of resistance-bearing units 13, which correspond to the metal bands 11 fastened on the outside of the cone. The core electrode 2 is supported by the metallic pin or bracket 14, which is 15 secured to a piece of channel iron, both of which are connected to a suitable ground. The resistance units 13 may be formed, as we have shown them, of different diameter disks of insulating material, which are set 20 loosely within the hollow cone of insulation 12. The disks of insulation 13 each contains a serpentine groove 16 having terminal clips 17 and 18 at the end of the groove, and a powdered or granular resistance material fills the groove. These disks of insulation 13 are made of porcelain or other refractory material and they may be made of a uniform size so that the same will be interchangeable for replacement and repairs. 25

25 The upper cone 9 is secured to the lower cone 12 by means of brackets 19 fastened by screws 20. In the form shown in Fig. 3 the upper cone 9 is also formed of sheet metal and it is secured to the lower cone by means 30 of a flanged plate or cap member 21.

A pair of through bolts 22 secures the cap 21 to the pin 14. In this form of construction the lower cone 10 is constructed of a number of independent sections held together by the bolts 22 and each bearing its own metal band electrode 11. These sections contain the same form of resistance material as that shown in Figs. 2 and 5, or they may be constructed with any other suitable form of resistance included in the body thereof. The plate 21 is made of insulating material or it may be made of metal and the bolts 22 suitably insulated therefrom. In Fig. 4 we have shown the upper cone 9 40 as constructed of insulating material bearing a number of metal strips 23 converging into a common point at the top. These strips 23 in this form of construction will define the path of the arc and will prevent the same from traveling sidewise as the arc rises. Attention is called to the form of air gap provided in the structure of Fig. 1. This gap is converging for the purpose of providing the selective discharge paths of 45 different capacity which we have mentioned above.

The air gap between the upper band 11 and the shell electrode is the shortest, but the resistance between this band and ground 45 is the greatest, so that it presents a dis-

charge path most easily overcome but of least capacity. If this path is insufficient to relieve the accumulated static, the next path requiring greater break down pressure but having greater discharge capacity breaks 70 down and so on down the row of electrode bands 11, each in turn requiring increased break down voltage but having increased discharge capacity. Hence the arc tends to break downward due to electrical conditions. 75 We have provided mechanical conditions tending to force the arc back, holding the same at a point where the discharge capacity is low.

The arc suddenly heats the air in the annular gap between the two surfaces. This causes a sudden expulsion of part of the same and a chimney effect or draft then occurs, which blows the arc upward, tending always to confine the arc to a path of low 85 discharge value or to break the arc completely.

We contemplate closing off, either completely or partially, the bottom of the annular air gap space in order to secure to a 90 greater or less extent the "bomb" or "explosion" effect which we shall describe more fully in connection with Fig. 6.

It is to be noted that we also contemplate sectionalizing the upper cone 9 and inserting 95 resistance between the sections, the resistance between the ring having the shortest air gap and ground being the critical resistance at which line surges and similar disturbances will be damped out, and of 100 such amount that the discharge occurring through this path will not materially lower the line potential.

The form of arrester shown in Fig. 6 comprises an outer shell electrode 1 and an 105 inner core electrode 2 in which the annular space between the two electrodes is open to the atmosphere only at one end. The other end of the gap is closed off by an annular ring of insulation 23'. The shell 1 is supported in a block of insulation 24 which is supported from an insulator 25 by means of suitable brackets 26, clamped to the insulator 25. The core 2 is connected to the ground wire by means of a bolt 27 which is 110 screwed into a socket formed in the shell of the core. The core electrode 2 is built up of a number of sections 28, separated by strips of insulation 29, to sectionalize the electrode. Each of the sections 28 is provided with extending flanges 30 which will tend to carry the arc over the insulation 29 without burning or overheating the same. The sections 28 are clamped together but 115 are insulated from each other and the hollow shell which is thus built up is filled with a powdered or granular resistance material, the paths through which are determined by the washers 29 of insulation. These washers are made to extend inwardly in order to 120 125 130

cause a greater or less distance electrically between the sections. The upper sections 28 are closed by a vent plug 31, which may also be used in filling the shell with resistance material. The lowermost sections 28 are divided into parts which thread together for convenience in assembling. We have shown this form of arrester as provided with a roof or cover 31' supported from the shell 10 by suitable brackets 32. This roof or cover is constructed of sheet metal, asbestos, porcelain, wood or any other suitable material. This form of arrester may be constructed to have the annular space forming the air 15 gap open to a certain degree at the bottom end, by removing the insulating ring 23' to allow a draft of air to pass up through the holes 33 and between the space of insulation 24 and the core 2. Thus a combined explosion and chimney effect will be secured inasmuch as rapid movement of air upon the initial formation of a spark will be impeded to such a great extent that the arc will be blown upward, and thereafter the movement 20 of the air into the lower part of the air gap will be so slow as not to be materially impeded.

In Fig. 8 we have illustrated another form 30 of arrester. In this form the outer shell electrode is composed of a bowl 1 of metal fastened by means of brackets or clips 33' to the insulator 34 upon which the same rests. The central core electrode 2 consists of a number of sleeves of resistance material 35 and conducting material arranged alternately and strung upon a rod or bolt 35 which passes down to the insulator 34 and connects with the pin 36, which is grounded. Alternate sleeves 37 are composed of metal 40 or conducting material, while the sleeves clamped between them, 38, are constructed of a material having a high specific resistance. The outer electrode 1 has suitable 45 openings at the bottom for draining the same. A bolt 35 which forms the central core of the core electrode and which is connected to ground through the pins 36 is insulated from all of the sleeves 37 and 38 except the lowermost one by means of a 50 tube or sleeve of insulation 39.

In the form of arrester shown in Fig. 9, both electrodes have been sectionalized and have resistance material connected between the sections. The resistance material forms 55 a symmetrical continuation of the conducting parts of the electrodes. The shell electrode 1 is supported in any convenient manner on the insulator 34 and consists of an upper flaring portion which is composed of 60 the alternate strip of resistance material 40 and the conducting strip 41 therebetween. The lower part of the shell electrode is formed of a cylindrical portion 42 of metal, such as copper. The lower portion of the 65 core electrode is also formed of a metal

sleeve 43 between which and the shell 42 the initial discharge is formed. The core electrode 2 is constructed of alternate resistance and conducting sections 38 and 37, clamped together by means of the bolt 40 70 which in this case is shown as a fiber rod. The lowermost section 43 of the core electrode is connected to the supporting stem 36 by means of the bolt or stud 44 passing up through the insulator 34. We have illustrated in this form of arrester the manner 75 in which the air gap, across which the spark is initially formed, can be adjusted. A plurality of concentric sleeves 45 formed of conducting material may be slipped inside of 80 the sleeves 42 to decrease the air gap to any desired extent. In this manner the arrester can be set for any standard voltage by inserting or removing the proper sleeve. It is to be noted that this form of adjustment 85 can also be applied to the arrester shown in Figs. 1, 6 and 8, previously described.

In Fig. 10 we have shown a form of arrester in which the outer shell electrode 1 comprises an upper flaring portion and a 90 lower elongated tubular portion 46 which is open at the bottom. The inner core electrode is constructed of alternate copper and resistance sleeves clamped together in the manner described in connection with Figs. 95 8 and 9. The shell electrode 1 is secured to the insulator 34 by means of suitable clamping brackets 47. A porcelain or other cover 48 is supported above the open flaring end of the shell electrode by means of the bolt 100 49, which serves to clamp the sections of the core electrode together. This form of arrester also provides paths which are of different impedance, so that selective paths for 105 different frequencies of current are provided. In this manner the upper adjustable sphere electrode 50 can be said to offer a suitable path for the discharge of one or more frequencies, while the adjustable sphere 51 offers a path suitable for a different 110 frequency.

In Fig. 11 we have illustrated one manner in which the arrester can be built in the inverted form. In this case the outer shell electrode 1 is inverted, that is, it has the flaring portion opening downward so that the arc formed between the outer and the inner electrode 2 will be moved downwardly instead of upwardly as in the previously described structures. The electrode 2 may be 115 constructed as described in connection with any of the foregoing embodiments or it may be constructed as shown, that is, of a number of bars of copper 52, between which and at right angles to which are clamped bars of 120 resistance material 53. The top of the core electrode is formed by a knob or sphere 54. The inner core electrode is supported upon a pin or bracket 54 which is connected to ground. The shell electrode 1 is supported 125 130

on a plurality of insulators 55 and is connected to the line. The action of this form of arrester is broadly the same as that shown in Fig. 1. The first discharge forms between the lowermost bar 52 or 53 and if the pressure is relieved the arc is extinguished by the explosion effect. If the discharge cannot be relieved at once, adjacent sections will discharge. The greater the discharge 10 the greater will be the tendency to blow the same out.

In Fig. 13 we have shown one manner in which a number of arresters of the type previously described may be connected in series. After a discharge occurs and an arc is once formed it is subject to being extinguished at each one of the gaps and inasmuch as the action of this type of arrester is quick and certain, the arc will be very 20 speedily extinguished. It is well known that the potential across the individual gaps of the arresters shown in Fig. 13 will not be uniform and that the greatest efficiency is not obtained by such arrangement.

25 We have shown in Fig. 14 an equalizing connection between a series of arresters so that the potential caused across all of the gaps is uniform. In this structure we provide an additional shell 1' which surrounds 30 the shell electrode, being separated therefrom by a sleeve of insulation. Each of the arresters is thus provided with an outer equalizing sleeve 1' and the sleeves are connected together by an equalizing connection 35 56 so that by means of the electrostatic balancing effect of the equalizing connection 56 the potential across all of the air gaps is the same.

We also contemplate connecting the various forms of arresters, above described, in other circuit relations to meet different operating conditions. The operation of the blowout means used in the various forms of arresters shown is essentially the same, 45 namely, that due to the expansion of the air caused by the heat of the arc a sudden movement of the air occurs which tends to carry the arc along with it and either hold the arc to a low discharge value or to break 50 the same completely.

We wish it to be understood that the difference between the explosive effect which we have heretofore mentioned, and the chimney effect, which has also been mentioned, 55 is largely a matter of degree. In both cases we depend upon a greater pressure upon one side of the arc, caused by the expanding air, than upon the other, with the natural consequence that the expanded air moves in the 60 direction in which there is the least resistance, or in which the pressure is the least. When the air gap is completely closed at the bottom the difference in pressure is caused by the expanding air being unable to 65 move out at the bottom, and hence is all

compelled immediately to move out through the open annular gap, carrying the arc along. When the lower portion of the air gap is open, movement of the arc is caused essentially by the difference in specific gravity of the two columns of air, that is, inside and outside of the shell electrode 1. In the form shown in Fig. 1 the discharge is formed initially between the upper ring 11 and the shell 3. If this path can relieve the 75 excess pressure, the arc does not strike downwardly and hence cannot cause any disturbance in the line, as the resistance prevents excessive discharge. The chimney effect or the bomb effect, if the air space is closed off, then 80 breaks the arc which is formed. If this path alone will not suffice, the adjacent paths will be called into play by the arc striking downwardly until the pressure is relieved. The tendency of the blowout arrangement is 85 to hold the arc to the paths of low discharge value and to destroy the arc completely. The greater the arc the greater will be the blowout tendency. Hence a very effective means tending to confine the discharge to the high resistance paths and for thereby preserving the line potential is provided.

In the forms illustrated, in which the lower end of the air gap is closed, the tendency is to keep the arc out or to drive it out 90 by the expansion of the gases due to the heat of the arc. The initial formation of the arc causes such a sudden expansion of the air as to constitute practically an explosion. This will be evident when it is recalled that 100 air if being heated from room temperature to the heat of the electric arc will be expanded to about 60 times its former volume at a given pressure. Consequently the tendency to drive the arc outward is very great 105 and the inclusion of resistance and breaking of the arc thereafter is performed very quickly. This, however, is not dangerous to the line, inasmuch as the resistance which is included in the sectionalized electrodes is 110 invariably included in the circuit before the arc itself is extinguished or broken. As a consequence no matter how rapid the movement of the arc outward, the arc will never be broken until such a resistance has been 115 included as will prevent line disturbances, for the movement of the arc outward, though rapid, is not commensurate in speed with the sudden increase in resistance caused by actual breaking of the arc, such as occurs 120 in the ordinary horn gap lightning arrester or similar type of arrester in which no resistance is included in the circuit previous to breaking the arc. We consider that this form of arrester is broadly new and desire 125 that the claims be construed with this in mind.

Numerous changes and modifications will at once suggest themselves to those skilled in the art and different mechanical struc- 130

tures will suggest themselves for meeting particular conditions, and we consider such changes, modifications and adaptations to come within the spirit and scope of our invention, and we desire the present specification and appended claims to be construed with this in mind.

What we claim as new and desire to secure by Letters Patent is the following:

- 10 1. The method of breaking an arc existing between two electrodes which consists first, in partially confining the gases about said electrodes, second, allowing the gases to expand in a given direction, third, moving the 15 arc with said expanding gases, fourth, and increasing the resistance of the circuit in which the arc is formed simultaneously with the movement of the arc.
- 20 2. The method of breaking an arc which consists in first, compressing the gases at the point of formation of said arc, second, decreasing the pressure upon one side of said arc, third, causing the compressed gases about said arc to move toward said side, fourth, 25 thereby carrying the arc with said gases, fifth, and simultaneously causing greater resistance to be included in the circuit of which the arc forms a part but exterior to the arc.
- 30 3. The method of breaking an arc which consists in the following: first, compressing the gases about said arc, second, decreasing the pressure upon one side of said arc, third, causing the compressed gases to move said arc with them, fourth, and simultaneously 35 with the movement of the arc inserting resistance in the circuit externally of said arc.
- 40 4. The method of breaking an arc which consists in first, partially confining the gases in which said arc is formed, second, allowing expansion of the gases heated by said arc in a given direction, third, moving said arc bodily or in part by the movement of said expanding gases, fourth, and thereby driving said arc to a path of increased circuit 45 resistance.
- 50 5. The method of breaking an arc which consists in first, partially confining the gases in which said arc is formed, second, causing the expansion of the gases to blow the arc along, third, and simultaneously increasing the ohmic resistance of the electrodes between which the arc exists.
- 55 6. The method of breaking an arc which consists in first, partially confining the gases in which said arc is formed, second, causing the expansion of the gases to blow the arc along, third, and simultaneously increasing the ohmic resistance of the circuit in which said arc is excluded, extraneously of said arc.
- 60 7. The method of breaking an arc which consists in first, partially confining the gases in which said arc is formed, second, allowing said gases to expand, third, to blow the arc along, fourth, and causing the arc by its

movement to include greater ohmic resistance in its own circuit.

8. The method of breaking an arc which consists in first, partially confining the gases in which said arc is formed, second, allowing the gases to expand, and third, blowing the 70 arc along between the electrodes, fourth, increasing the length of the arc, fifth, and simultaneously increasing the ohmic resistance of the circuit exterior to the arc.

9. In combination a pair of concentric 75 electrodes having an explosion chamber formed therebetween, the inner one of said electrodes being sectionalized and resistances connected between said sections.

10. In combination an inner electrode and 80 an outer shell electrode inclosing said inner electrode, said electrodes forming an annular chamber therebetween, said chamber being constricted intermediate its ends, one of said electrodes comprising a plurality of 85 metal sections and resistances connecting said sections.

11. In combination an inner electrode and an outer electrode substantially concentric with said inner electrode and inclosing the 90 same, said electrodes forming an annular chamber between them, said chamber being constricted intermediate the ends, the lower part of said inner electrode comprising a plurality of metal sections connected together by resistances and the upper portion 95 of said inner electrode comprising a conical conducting section.

12. In combination a pair of concentric electrodes with an explosion chamber 100 formed therebetween, one of said electrodes being sectionalized and resistances connected between said sections.

13. In combination a pair of concentric electrodes with an explosion chamber 105 formed therebetween, one of said electrodes comprising a plurality of metal sections connected by resistances.

14. In combination a pair of concentric electrodes one of said electrodes comprising 110 a plurality of symmetrical sections, and resistances connecting adjacent sections of said electrode.

15. As a means for breaking an arc, a single central sectionalized electrode and an 115 inclosing shell electrode surrounding said central electrode, said electrodes having an annular space between them forming an air gap, said space being open to the atmosphere at one end, said central electrode being 120 conductively continuous.

16. In combination a pair of electrodes having a gap therebetween, one of said electrodes being sectionalized, resistances connected between said sections, said sectional 125 electrode and said other electrode forming a gap converging upward.

17. In combination a pair of vertically ex-

tending electrodes having a gap therebetween, one of said electrodes being sectionalized, resistances connecting said sections, said electrode having an air gap of a length 5 greater at the end of less resistance than at the end of greater resistance of said electrode.

18. The method of relieving excessive pressure which consists in causing the accumulated 10 excessive pressure to discharge in a spark or arc through paths requiring successively greater pressures to cause the same to operate and having successively greater discharge capacity and simultaneously creating a tendency to drive bodily the arc or spark to the paths of least discharge capacity and then breaking said arc or spark.

19. The method of relieving excessive pressure which consists in causing the accumulated 20 excessive pressure to discharge in a continuous arc or spark through paths requiring successively greater pressure to cause the same to operate and having successively greater discharge capacity and simultaneously creating a tendency commensurate with the discharge occurring to confine the arc or spark to the paths of least discharge capacity and then breaking said arc or spark.

20. The method of relieving excessive pressure which consists in starting the discharge or arc through a path having relatively less break-down strength and relatively less discharge capacity, then causing 35 said discharge or arc to move bodily to an adjacent path having greater discharge capacity, said movement being progressive in accordance with the quantity of excess pressure to be relieved, then creating a blow-out 40 force tending to drive said discharge or arc bodily to a path of relatively less discharge capacity and then breaking the discharge or arc.

21. The method of relieving excessive 45 electrical pressure which consists in initiating the discharge or arc through a path of relatively less discharge capacity and relatively less breakdown strength then bodily moving the discharge or arc to an adjacent 50 path of relatively greater discharge capacity and relatively greater breakdown strength, then moving said discharge or arc to a path of less discharge capacity and then lengthening the arc and finally breaking the same.

55 22. The method of relieving excessive

electrical pressure which consists in initiating a discharge or arc through a path of relatively less discharge capacity and relatively less break-down strength, then bodily moving the discharge or arc to an adjacent 60 path of relatively greater discharge capacity and relatively greater break-down value, and simultaneously confining or partially confining the gases in which said arc is formed, then causing the expansion of the 65 gases to move said arc to a path of less discharge capacity and then lengthening the arc and finally breaking the same.

23. In combination a plurality of juxtaposed discharge gaps, said gaps having successively greater discharge capacities and requiring successively greater voltages to break down the same, said gaps having means tending to drive the discharge from the gaps of greater discharge capacity to 70 the gaps of less discharge capacity, said gaps being positioned adjacent each other so that the spark or arc can move bodily from one gap to another without cessation.

24. In combination a plurality of juxtaposed spark gaps, said gaps requiring successively greater voltages to break down the same and having successively greater discharge capacity, said gaps having means tending to drive the spark from the gaps of 80 greater discharge capacity to the gaps of less discharge capacity, said means acting in degree commensurate with the size of the spark and a common flaring portion for breaking the spark or flow of current. 90

25. In combination a plurality of adjacent superposed spark gaps, the upper spark gaps being of relatively less length than the lower spark gaps and being of graduated length, the longer spark gaps having relatively greater discharge capacity, said gaps having means tending to drive the spark from the gaps of greater discharge capacity to the gaps of less discharge capacity and a common flaring or blow-out portion common to all of said gaps. 95

In witness whereof, we hereunto subscribe our names this 18th day of March A. D. 1915.

EDMUND O. SCHWEITZER.
NICHOLAS J. CONRAD.

Witnesses:

EMIL W. STEEGE,
FRANK W. SKELDING.
